TOOL FOR REMOVING AND HOLDING A RADIATOR CAP

George B. Cox, Knoxville, Tenn., assignor of one-half to Lyman J. Weaver, Knoxville, Tenn.; Eunice Cox, administratrix of the estate of said George B. Cox, deceased

Substituted for abandoned application Serial No. 453,907, September 2, 1954. This application August 28, 1958, Serial No. 757,853

1 Claim. (Cl. 81—125)

This application is substituted for my prior application, filed September 2, 1954, Serial No. 453,907 (now abandoned).

This invention relates to tools for removing and holding radiator caps, especially the caps of vehicle radiators where the temperature of the water in the radiator is excessively hot.

It is well known that when the water in the circulating system of an automobile engine becomes very hot, it is difficult and dangerous to remove the radiator cap for refilling the system or for cooling, due to the steam pressure built up in the top of the radiator which causes steam and hot water to be blown outward through the opening in the radiator pipe when the cap is removed. This may cause injury to a person removing the cap, due to scalding.

It is general practice for an attendant to place a cloth over the radiator cap in removing it, but this is unsatisfactory because it requires the hand and arm of the attendant to be extended over the radiator when the cap is removed and is insufficient protection against scalding or burning.

No satisfactory tool has been developed or put into general use for removing the cap without likelihood of injury to the attendant.

One object of the invention is to provide in a tool a socket with undercut recesses to enable the radiator cap to be removed safely while the attendant is located at a suitable distance from the point of danger at the top of the radiator.

Another object of the invention is to improve the construction of tools of this character, which may be applied to the cap of a radiator for the removal thereof in a simple manner and without danger to the attendant.

These objects may be accomplished, according to one embodiment of the invention, by the provision of a head constructed to fit over a radiator cap with facilities for engaging the latter to cause loosening of the cap upon rotation of the head. A handle is attached to the head for turning the latter to loosen and remove the radiator cap. The handle preferably is of sufficient length so as to enable the workman to manipulate the head and remove the cap while located at a convenient distance therefrom. The construction may be simple and inexpensive to build and use and will be entirely effective for the intended purpose.

This embodiment of the invention is illustrated in the accompanying drawings, in which:

Fig. 1 is a side elevation of a radiator pipe and cap, showing the tool applied thereto in section;

Fig. 2 is a front elevation of the tool detached;

Fig. 3 is a side elevation thereof; and

Fig. 4 is a detail cross section on the line 4—4 in Fig. 2.

The invention is shown applied to a radiator cap, generally designated by the numeral 1, secured upon a radiator filling pipe 2. Most radiator caps are formed

2

with a pair of ears 3 extending axially on opposite sides of the center thereof, although some of these caps are provided with four ears extending radially at 90° from each other. Usually the cap is screw threaded upon the pipe 2 or interconnected therewith for removal by a turning motion.

The tool illustrated in the embodiment shown in the drawings comprises a head, generally indicated at 4, preferably circular in outline, as shown in Fig. 2, with a closed back wall 5, and an annular side wall or rim 6 of appreciable thickness which defines a front access opening, as indicated at 7. This forms a cupped enclosure adapted to fit over the body of the cap 1 to receive the latter entirely within the rim 6, substantially as illustrated in Fig. 1.

In order to accommodate the ears 3 usually provided on the radiator cap, the rim 6 is provided with a plurality of semicircular notches 8 in the inner periphery thereof and extending from the front face of the rim 6 to the back wall 5. The tool may be provided with either two such notches 8 or with four, as shown in Fig. 2, or with other suitable number, according to the number of ears 3 customarily provided on the radiator cap 1. The rim 6 is also provided with undercut recesses 9 extending circumferentially from the respective notches 8 and formed as undercut portions in the rim to receive therein the ears 3 of the cap when the head 4 is turned relative thereto. This forms a locking connection between the head and the cap which will provide for removal of the cap from the pipe 2 by a lifting motion of the head. One of these recesses is illustrated in section in Fig. 4.

The head 4 may be built up of separate parts or, according to the illustrated embodiment, may be in the form of a casting of aluminum, steel, or other suitable material, as desired.

The back wall 5 of the head is provided with a sleeve or ferrule 10 formed thereon or secured thereto. One end of a handle 11 is telescoped into the sleeve or ferrule 10 where it may be secured in any suitable manner as by a pin 12. The handle 11 is preferably bent at right angles so as to provide an elongated portion of substantial length which will extend out and away from the radiator cap a sufficient distance to enable grasping and holding by an attendant in removing the radiator cap without danger of scalding or burning by the steam of the radiator.

In using the tool, it will be apparent that the cap 1 is normally in place on the filling pipe 2 of the radiator, as shown in Fig. 1. The access opening 7 of the head 4 is brought into registry with the cap 1, and the annular rim 6 is then telescoped over the cap 1, the ears 3 on the cap being received within the notches 8 in the head. The handle 11 will extend out in a horizontal direction from the radiator and may be manipulated by the attendant. Upon shifting the handle in a counter-clockwise direction relative to the top of the radiator cap, the ears 3 will be received within the recesses 9 in the head, and continued rotation of the latter by the handle 11 will cause the ears to abut against the ends of the recesses so that continued motion of the head by the handle 11 will shift the cap sufficiently to disengage its connection with the filler pipe 2 and thus allow lifting off of the cap from the filler pipe by the handle. If an accumulation of steam is contained within the top of the radiator, this may be discharged without danger to the attendant, due to his safe distance from the cap. In this way the cap may be removed safely without danger and in a very simple and expeditious manner.

The construction of the tool is simple and inexpensive, enabling it to be manufactured at low cost, providing an effective tool for the purpose.

While the invention has been described in one embodiment, it is recognized that variations and changes may be made therein without departing from the invention, as set forth in the claim.

I claim:

A tool for removing radiator caps comprising a head having a wide closed back with a surrounding rim and having a relatively shallow recess within the rim to receive a radiator cap therein, said recess being substantially circular in outline on a radius appreciably greater than the depth of the recess, said rim having a plurality of semicircular notches in the inner side thereof to receive ears on the radiator cap when the head is telescoped over the latter, said rim having undercut recesses at the inner periphery thereof in open communication at one end with the notches, each of the undercut recesses hav-

ing the opposite end concave on an arc extending to the inner face of the rim, and a handle secured to the closed back of the head substantially at the axis thereof and extending axially and radially outwardly from said head.
